United States Patent

Des. 235,954

Patented July 22, 1975

235,954

STUDY CARREL

Gustave T. Holland, Burlington, Ontario, Canada, assignor to Learning Consultants Limited, Belleville, Ontario, Canada

Filed Sept. 24, 1973, Ser. No. 399,811

Term of patent 14 years

Int. Cl. D6—99; XD6—04

U.S. CL. D6—181

FIG. 1

FIG. 2

FIG. 1 is a perspective view of a study carrel showing my new design, taken obliquely from behind and beneath; and

FIG. 2 is a perspective view of the study carrel of FIG. 1, taken obliquely from above and in front.

The outer face of the side not shown is a mirror image of the outer face shown while the inner face of the side wall not shown in FIG. 2 is like the inner side face shown therein.

I claim:

The ornamental design for a study carrel, as shown and described.
